UNITED STATES PATENT OFFICE.

JAMES REID, OF WATERVLIET, NEW YORK, ASSIGNOR TO FEDERAL SIGNAL COMPANY,
A CORPORATION OF NEW YORK.

DETECTOR-BAR.

1,157,726.

Specification of Letters Patent.

Patented Oct. 26, 1915.

Application filed April 27, 1912. Serial No. 693,754.

To all whom it may concern:

Be it known that I, JAMES REID, a citizen of the United States, and a resident of Watervliet, county of Albany, and State of New York, have invented certain new and useful Improvements in Detector-Bars, of which the following is a specification.

This invention relates to improvements in detector bars and seeks to provide a novel and useful arrangement whereby the bar may be moved into two detecting positions, one such position being against the tread of a wheel, and the other detecting position being against the side face of a wheel.

15 In the present invention I make use of a swinging arm to move the bar into one detecting position and additional means of a suitable nature to move the bar into its other detecting position. In the present instance, said swinging arm is arranged to move the bar upward against the tread of a wheel and a cam is employed to move the bar inward against the side face of a wheel.

20 In its broader aspect, the invention is capable of being embodied in various forms.

25 In the accompanying drawings forming part of this specification, and in which like reference numerals designate corresponding parts, Figure 1 is a perspective view, the parts being in normal position. Fig. 2 is a sectional elevation on the line 2—2 of Fig. 3 showing the bar in its extreme inward position over the head of the rail. Fig. 3 is a plan view showing the parts in the same position as in Fig. 2. Fig. 4 is a side view of the clip.

30 Referring now to the particular features as shown in the drawings, 1 is the rail and 2 is the detector bar, preferably formed of angle iron, and provided with an operating rod 3 for imparting longitudinal movement to the bar.

35 4 is a clip secured to the rail by bolts 5 and provided with a bearing 6 for the rotatable pin 7.

40 8 is a swinging arm provided with a slot 9 to receive the flattened projecting end of the pin 7. The arm 8 is secured to the pin 7 by a pivot pin 10 held in place by a cotter pin 11.

45 The clip is provided on its outer end beneath the pivot pin 10 with the cam face 12

50 terminating in recesses 13 and 14. The clip is also provided on its outer end above the pivot pin 10 with two cam faces 15 and 16 between which cam faces there is provided a recess 17. The upper end of the arm 8 is pivotally secured to the bar 2 by the pivot pin 18. The arm 8 projects below the pin 10 to provide a follower 19 designed to 55 traverse the cam 12, and the inner face of the arm 8 traverses the cams 15 and 16 and the recess 17. The slot 9 in the arm 8 is larger than the end of the pin 7 which it receives to permit the arm to tilt toward and 60 from the rail.

65 In the normal position, as shown in Fig. 1, the bar is slightly below the plane of the rail head and slightly beyond the side face thereof. While the bar is in this position, 70 the arm 8 above the pivot pin 10 is resting against the cam 15 and the follower 19 is in the recess 14. When the bar is moved longitudinally, it is carried upward by the arm 8, which exerts an upward thrust to the bar, 75

so as to meet the tread of a wheel on the rail if such wheel is projecting beyond the rail head. If the wheel is not so projecting, further movement of the bar causes it to move inward across the head of the rail 80 so as to contact with the side face of a wheel if such wheel is on the rail but is not projecting beyond the head thereof. This inward movement is imparted to the bar by an inward thrust due to the cam 12 along 85

which the follower 19 has been traveling during the movement of the arm 8. This cam thrusts the lower end of the arm outward and the upper end of the arm inward, the extreme inward position of the bar being reached when the arm 8 reaches about its vertical or mid-position. If no wheel is present on the rail, the longitudinal movement of the bar continues and the upper part of the arm finally reaches the cam 16 90 at the same time the follower 19 reaches the recess 13. Thereupon, the cam 16 tilts the upper end of the arm 8 outward, thereby exerting an outward thrust to the bar and withdrawing the bar from over the head of 100 the rail and permitting the bar to finally come to rest beyond and beneath the rail head. When the bar is moved longitudinally in the opposite direction, it moves inward

and outward over the head of the rail in the same way as before, the inward movement of the bar being effected by the action of the cam 12 on the follower 19 as the follower makes its return movement, and the outward movement of the bar being effected by the action of the cam 15 on the arm 8.

The invention may be embodied in various forms without departing from the scope 10 thereof, the preferred form being that shown in the drawings.

What is claimed and desired to be secured by Letters Patent is:—

1. A detector bar designed and adapted 15 to move into two detecting positions, one detecting position being against the tread of a wheel and another detecting position being against the side face of a wheel; and means comprising swinging arms and cam 20 faces for moving said bar into said detecting positions.

2. A detector bar designed and adapted to move into two detecting positions, one detecting position being against the tread of 25 a wheel and another detecting position being against the side face of a wheel; and means comprising swinging arms and cam faces acting on said arms for moving the bar into said detecting positions.

30. 3. A detector bar designed and adapted to move into two detecting positions, one detecting position being against the tread of a wheel and another detecting position being against the side face of a wheel; and 35 means comprising swinging arms and cam faces for moving the bar into said detecting positions, the swinging arms exerting an upward thrust to carry the bar upward and the cam faces exerting a thrust to carry the 40 bar inward.

4. A detector bar designed and adapted to move into two detecting positions, one detecting position being against the tread of a wheel and another detecting position being 45 against the side face of a wheel; and means comprising swinging arms and cam faces for moving said bar into its detecting positions, the swinging arms exerting an upward thrust to the bar and the cam faces arranged to bear upon said arms to exert an 50 inward thrust to the bar.

5. A detector bar designed and adapted to move into two detecting positions, one detecting position being against the tread of 55 a wheel and another detecting position being against the side face of a wheel; clips secured to the rail; swinging arms pivoted to said clips and to said bar to move the bar against the tread of a wheel; and means in 60 addition to said arms to exert a thrust to bring the bar against the side face of a wheel.

6. A detector bar designed and adapted 65 to move into two detecting positions, one detecting position being against the tread of

a wheel and another detecting position being against the side face of a wheel; clips secured to the rail; swinging arms pivoted to said clips and to said bar to move the bar against the tread of a wheel; and cam faces 70 to exert a thrust to thereby bring the bar against the side face of a wheel.

7. A detector bar designed and adapted to move into two detecting positions, one detecting position being against the tread of a wheel and another detecting position being against the side face of a wheel; clips secured to the rail; swinging arms pivoted to said clips and to said bar to move the bar against the tread of a wheel; and cam faces 80 on said clips to exert a thrust to thereby bring the bar against the side face of a wheel.

8. A detector bar designed and adapted to move into two detecting positions, one 85 detecting position being against the tread of a wheel and another detecting position being against the side face of a wheel; clips secured to the rail; swinging arms pivoted to said clips and to said bar to move the bar 90 against the tread of a wheel and also arranged to tilt toward the rail; and cam faces on the clips acting on said arms for moving the bar inward against the side face of a wheel.

9. A detector bar designed and adapted to move into two detecting positions, one detecting position being against the tread of a wheel and another detecting position being against the side face of a wheel; and 100 means comprising swinging arms and cam faces for moving the bar into and out of its detecting positions.

10. A detector bar designed and adapted to move into two detecting positions, one 105 detecting position being against the tread of a wheel and another detecting position being against the side face of a wheel; and means comprising swinging arms for moving said bar into and out of one of said detecting positions and also comprising cam faces acting on said arms for moving said bar into and out of its other detecting position.

11. A detector bar designed and adapted 115 to move into two detecting positions, one detecting position being against the tread of a wheel and another detecting position being against the side face of a wheel; and means comprising swinging arms for moving said bar into and out of its detecting position against the tread of a wheel and also comprising cam faces for moving said bar into and out of its detecting position against the side face of a wheel.

12. A longitudinally moving detector bar designed and adapted to move into two detecting positions, one detecting position being against the tread of a wheel and another detecting position being against the side 130

face of a wheel; and means comprising swinging arms and cam faces for moving said bar into its detecting positions.

13. A longitudinally moving detector bar 5 designed and adapted to move into two detecting positions, one detecting position being against the tread of a wheel and another detecting position being against the side face of a wheel; and means comprising 10 swinging arms for moving said bar into its detecting position against the tread of a wheel and also comprising cam faces for moving said bar into its detecting position against the side face of a wheel.
14. A longitudinally moving detector bar 15 designed and adapted to move into two detecting positions, one detecting position being against the tread of a wheel and another detecting position being against the side 20 face of a wheel; clips secured to the rail; swinging arms pivoted to said clips and to said bar to move the bar against the tread of a wheel and also arranged to tilt toward the rail; and cam faces on said clips acting on said arms for moving the bar inward against the side face of a wheel.

of a wheel; and means in addition to said arms to exert a thrust to bring the bar against the side face of a wheel.

15. A longitudinally moving detector bar 25 designed and adapted to move into two detecting positions, one detecting position being against the tread of a wheel and another detecting position being against the side 30 face of a wheel; clips secured to the rail; swinging arms pivoted to said clips and to said bar to move the bar against the tread of a wheel and also arranged to tilt toward the rail; and cam faces on said clips acting 35 on said arms for moving the bar inward against the side face of a wheel.

In testimony whereof, I have signed my name to this specification, in the presence of two subscribing witnesses.

JAMES REID.
